His Attorney.

UNITED STATES PATENT OFFICE.

WILLIAM D. COOLIDGE, OF SCHENECTADY, NEW YORK, ASSIGNOR TO GENERAL ELECTRIC COMPANY, A CORPORATION OF NEW YORK.

X-RAY APPARATUS.

Application filed January 31, 1921. Serial No. 441,160.

The present invention comprises an improved X-ray apparatus which is particularly adapted for use in radiography.

It is the object of my invention to provide an X-ray apparatus which is safe electrically and which at the same time may be readily moved to a desired position and maintained firmly in that position when taking a picture.

10 My invention is particularly applicable to an apparatus in which an X-ray tube is immersed in a bath of oil together with the supply transformer, in order to insure safety from electrical shock to the operator and patient. Although the X-ray tube may be made very small and light in an oil-immersed outfit, the weight of the apparatus as a whole including the transformer, casing, and the oil filling, necessarily is heavier 15 than the ordinary X-ray tube. When supporting such a relatively heavy oil-immersed apparatus with relation to the part to be radiographed or otherwise examined or treated, the supporting arm must either be 20 made heavy and bulky, or else it tends to vibrate or oscillate, thereby tending to produce indistinct radiographs. I have found that one difficulty is caused by the tendency of the apparatus to rebound somewhat when 25 moved to a desired position due perhaps to springiness and lost motion in the supporting members. I have discovered that a relatively light support may be satisfactorily used for an X-ray outfit by providing 30 a compressible member or buffer attached to the movable X-ray apparatus which may be positioned in contact with a part to be subjected to X-rays, and which will tend to follow up any rebound of the device as 35 a whole, thereby maintaining contact with the part to be subjected to X-rays. The novel features of my invention will be pointed out with greater particularity in the appended claims.

40 In the accompanying drawing, Fig. 1 shows in perspective an embodiment of my invention; Fig. 2 is a longitudinal section of a part of my improved device; Fig. 3 is a detail view partly in section of a suitable pivotal support; and Fig. 4 is a detail sectional view of a part of the supporting bracket.

The apparatus illustrated by Fig. 1 com-

prises a closed receptacle 1 in which are located an X-ray tube and a transformer (not shown) the X-ray tube being connected to the transformer terminals. An insulating liquid within the receptacle, preferably a mineral oil, surrounds the X-ray tube, transformer, and connecting parts. As shown in the drawing, the only exposed part of the low tension supply circuit are short sections of one of the conductors 17 which for the greater part of its length is contained within hollow members of the supporting bracket. The X-ray tube may be conveniently mounted upon the supports attached to the cover 2 of the receptacle 1. The cover contains a window 3 which is permeable to X-rays. An X-ray apparatus of this general type is described in Waite Patent No. 1,334,936 issued March 23, 1920. As shown in this patent, the high tension connections between the transformer secondary and the X-ray tube terminals are concealed by being 55 buried in the oil within the containing tank. The receptacle 1 with its contained parts is connected by a holder 4 to a movable bracket 5, which may be of any suitable construction 60 adapted to render the outfit freely movable to a desired position, that is, the several joints 18 in the support afford a limited universal movement. The particular bracket illustrated comprises a plurality of hinged members which enable the receptacle 1 to 65 be moved outwardly in a substantially horizontal plane as well as up and down in substantially a vertical plane. The parallel arms 5', 6, are hinged movably to the holder 4 and are in turn movably connected to a 70 member 7. The other parts of the bracket, namely, the paired rods 8, 9, and 10, 11 and the connector 12 are constructed to enable the X-ray device to be freely moved in any 75 desired direction. The weight of the receptacle 1 and contained parts is equilibrated by a spring 13, (see Fig. 4) contained within a hollow rod 14, and connected to a cable 15, winding over an eccentric drum 16, shaped so as to counterbalance the X-ray 80 apparatus comprising the receptacle 1 and its contents in all positions. By this means stability is obtained in any position with the limits of movement of the apparatus 85 without clamping devices. 90

Projecting from the receptacle 1 opposite

the window 3 of the X-ray tube is a tube 19 in line with the beam of X-rays emerging from the X-ray tube. As shown in Fig. 2 a second tube 20 telescopes within the tube 19 bearing against a spring 21.

When the described apparatus is moved against an object or patient to be radiographed, the spring 21 is compressed slightly when the apparatus is positioned so that 10 when the receptacle 1 tends to move away from the desired position, the follow-up movement of the slightly compressed spring 21 causes the tube 20 to remain in contact with the part which is intended to receive 15 X-rays.

The nature of the yielding extension from the X-ray outfit permits motion in only one direction that is parallel with the axis of the tubes 19, 20; in other directions the outfit 20 is rigid.

Preferably, the post 22 of the supporting bracket is provided at its base with a light coiled spring 23, one end of the spring being connected to the post 22 and the other end 25 to the pivot 24, so that a rotation of the post 22 places a torsion upon the spring. The position of the X-ray outfit with respect to the patient preferably is so chosen that the spring at the base of the post 24 exerts 30 a slight restoring force when the outfit is displaced from a given position which is chosen to urge the X-ray tube container against the patient or object to be radiographed. By the action of the spring 23, 35 torsion is exerted whereby the X-ray apparatus is steadied and held against the part to be radiographed thereby coacting with the spring 21 to steady the apparatus thus enabling a clear picture to be taken. The 40 outfit is freely movable and adjustable for the operator to different positions. The advantages of this lightness, safety, freedom of motion and stability in any location particularly for such work as dentistry will 45 readily be appreciated.

What I claim as new and desire to secure by Letters Patent of the United States, is:—

1. An X-ray apparatus comprising an 50 X-ray bulb, a housing therefor, a support

permitting a limited universal motion for said housing, an equipoise counterbalancing said housing with its contents, and a steady- 55 ing device connected to said housing and adapted to be placed in contact with a sub- ject to receive X-rays, said device being compressible by a slight force exerted by said support toward the subject to be X-rayed.

2. An X-ray apparatus comprising an 60 X-ray tube, a container therefor, a movable support for said container, and a tubular extension fixedly connected to said container and being constructed to be compressible in an axial direction. 65

3. An X-ray apparatus comprising a container means therein for generating a beam of X-rays, a telescoping tube mounted upon said container and being aligned to transmit said beam of X-rays, and a spring 70 connection between the telescoping members of said tube.

4. An X-ray apparatus comprising an 75 X-ray tube, a source of high potential current connected thereto, a container having a window for said tube and source, supporting means for said tube permitting a limited universal movement, means for counterbalancing said container to remain at rest in any position in a vertical plane, 80 means for urging said device to a given position in a horizontal plane and a yielding telescoping extension for said container adjacent said window.

5. An X-ray apparatus comprising an 85 X-ray bulb, a transformer connected thereto, a common enclosure for said members in which all high tension parts are contained, a supporting bracket for said enclosure having joints permitting movement in 90 different planes, an equipoise for said enclosure and contained members whereby the same is counterbalanced in all positions and means for exerting a slight restoring force upon said outfit when given a rotational displacement from a given position in a horizontal plane. 95

In witness whereof, I have hereunto set my hand this 27th day of January, 1921.

WILLIAM D. COOLIDGE.
